UNITED STATES PATENT OFFICE.

FRANCIS M. HENRY, OF MINNEAPOLIS, MINNESOTA.

BOAT.

Application filed February 3, 1927. Serial No. 165,555.

My present invention relates to improvements in boats and more particularly to power-propelled boats of the type commonly called tow boats. Said invention further 5 provides a novel arrangement of coupling barges in respect to the improved tow boat.

While the improved tow boat is intended for general use, it is especially designed for use in shallow channels.

10 Generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a plan view of a tow boat and fleet of barges having the invention embodied therein;

Fig. 2 is a front elevation of the barges on an enlarged scale;

Fig. 3 is a side elevation of the improved tow boat;

25 Fig. 4 is a plan view of the same, with some parts removed;

Fig. 5 is a view in longitudinal vertical section taken on the line 5—5 of Fig. 4;

Fig. 6 is a rear view of the improved tow 30 boat with the bumper removed;

Fig. 7 is a fragmentary view partly in elevation and partly in transverse vertical section taken on the line 7—7 of Fig. 4; and

35 Figs. 8 to 11, inclusive, are views in transverse vertical sections taken on the lines 8—8, 9—9, 10—10 and 11—11 of Fig. 4, respectively, with some parts removed.

The hull of the tow boat includes a steel 40 shell 12 built around a steel structure. This steel structure, as shown, includes two laterally spaced longitudinal girders 13 at each side of the hull, two intermediate longitudinal girders 14, and a plurality of transverse 45 girders 15. The hull has a closed deck 16, and the longitudinal girders 13 and 14 and the transverse girders 15 divide the hull into a plurality of bulk heads 17. These bulk 50 heads 17 may be used for the storage of fuel oil, and if necessary, certain thereof may be used for water ballast.

The bottom of the hull, at the sides thereof, has convex sections 18 and between said sections an arched or concave section 19.

55 The outer longitudinal edge portions of the convex section 18 extend into the sides of

the hull. Said concave section 19, together with the connected portions of the convex sections 18, afford a tunnel 20 which extends the full length of the hull and is unob- 60 structed. This tunnel 20 forms one of the salient features of the invention.

It will be noted that the hull is relatively deep at its side sections and relatively shallow at its intermediate section. It will also 65 be noted that the crown of the tunnel 20 is substantially at the surface of the water α so that the bottom of the two boat rests on the water throughout its full width.

Two laterally spaced sponsons 21 are 70 formed as integral parts of the hull and form rear extensions of the deep side sections thereof at the sides of the tunnel 20. It will be noted that the two pairs of girders 13 extend into the sponsons 21 and form 75 parts thereof. The deck 16 extends rearward and covers the two sponsons 21.

Heavy bumpers 22 are rigidly secured to the prow of the hull in alignment with the two inner girders 13 and the two intermediate 80 girders 14. A heavy transverse horizontal bumper 23 is rigidly secured to the rear ends of the sponsons 21 and forms a cross-tie member for said sponsons.

Front, intermediate and rear trusses 24 85 extend transversely above the deck 16 and form extensions of certain of the girders 15. Built on the deck 16 around the trusses 24 is a housing 25 having the necessary doors and windows, and it will be noted that this 90 housing covers both sponsons 21. A vertically movable pilot house 26 extends through the top of the housing 25 at the front thereof. The purpose of thus mounting the pilot house 26 is to permit the same to be lowered so that the boat may go under low 95 bridges. Various different means may be employed for raising and lowering the pilot house 26, such as heavy screws 27, one of which is shown in Fig. 3. Extending 100 through the roof of the housing 25 just back of the pilot house 26 is a stack 28 for exhaust gases from the engines. These pedestals 31 are mounted directly over the girders 15 and rigidly secured in respect thereto. 105

A paddle wheel 29 comprises two axially spaced sections independently journaled on a fixed horizontal transverse shaft 30, the end portions of which are rigidly secured in pairs of axially spaced pedestals 31 on the 110 sponsons 21 at the longitudinal centers thereof. As the shaft 30 is rigidly secured to

the sponsons 21 by the pedestals 31, it affords a rigid crosstie member for said sponsons. Anti-friction bearings are interposed between the paddle wheel sections and the 5 shaft 30.

A motor bed 32 is located over each sponson 21 and has a three-point suspension. The front end of each motor bed 32 is in the form of a V and is supported on the deck 10 16, at the transverse center of said bed, by a ball and socket joint 33. These ball and socket joints 33 are located directly over the transverse girders 15 between the stern of the hull and the sponsons 21. On the 15 rear ends of the side members of the motor beds 32 are axially aligned bearings 34 journaled on the shaft 30 between the pairs of pedestals 31.

Mounted on each motor bed 32 is an electric motor 35 having on the inner end of its shaft a spur pinion 36 which meshes with a spur gear 37 on the adjacent end of the paddle wheel 29. Obviously, the three-point suspension of the motor beds 32 and 20 the location of two of their bearings on the fixed shaft 30 always keep the motors 35 permanently and definitely positioned in respect to the shaft 30, irrespective of any warping or twisting of the hull of the boat. 25 With the motors 35 thus mounted, their pinions 36 always accurately mesh with the gears 37.

It is highly important to note that the paddle wheel 29 is directly back of the 30 tunnel 20 so as to get the full benefit of all water passing through said tunnel. A splash board 38 for the paddle wheel 29 is located in front thereof and mounted on the top of the housing 25.

40 Two laterally spaced Diesel engines 39 are mounted on the deck 16 in balanced arrangement at the front of the hull. Directly back of each of these engines 39 is a generator 40. For the purpose of this case it will not be 45 necessary to show the wiring from the generators 40 to the motors 35. Neither is it necessary to show the control of each motor 35 which will be located in the pilot house 26.

50 On the deck 16, at each side of the hull, is a plurality of cleats 41 for use in tying up the tow boat to a dock, and at the prow of said boat is a pair of cleats 42.

A pair of laterally spaced rudders 43 are 55 mounted on the hull and located in the tunnel 20 at the rear end thereof, and a pair of rudders 44 are mounted on the sponsons 21 and located thereunder. These rudders 43 and 44 are of the balanced type 60 and the controls therefor are not shown.

Mounted on the deck 16, forward of the housing 25, is a pair of bitts 45.

The tow boat just described is especially adapted for use in shallow channels. Even 65 when the deepest part of the hull is just out

of contact with the bed of a channel or when passing over a sand bar or shoal, the paddle wheel 29 is getting the full benefit of all of the water to substantially its full depth as the same passes through the tunnel 70 20. The provision of the tunnel 20 makes it possible to mount the paddle wheel 29 close to the stern of the boat and between the sponsons 21 as it does not rely on a supply of water coming in from the sides of 75 the boat.

The sections of the paddle wheel 29, as previously stated, are independently operated and may be driven at the same or different speeds or in the same or reverse directions so as to facilitate the control of the boat. When going with the current, the boat may be propelled by only one section of the paddle wheel 29 and hence only one motor need be operated. Said paddle wheel 80 29 is fully protected by the hull and sponsons 21 at the front and sides and at the rear by the heavy bumper 23.

While reference has been made to only the longitudinal and transverse girders and the 90 transverse trusses, the boat will be further reinforced by crosstie rods and the like.

In Fig. 1 the tow boat is shown pushing a fleet of four barges loaded with coal 2. These barges 46 are arranged in front and 95 rear pairs, the latter of which are directly engaged by the bumpers 22 and the barges of the two pairs having abutting contact.

The two front and rear pairs of barges 46 are held laterally spaced, to leave a 100 channel 47 therebetween, by a pair of heavy frames 48. These frames 48 directly engage the opposing sides of each pair of barges 46 and have laterally projecting top members 49 which rest on the top of the decks of 105 said barges and support the frame 48 therefrom. The rear pair of barges 46 is lashed to each other and to the tow boat by a cable 50 passed around the cleats 42. The four barges 46 at their adjacent ends are lashed 110 together by a cable 51, and the two front barges 46, at their front ends, are lashed together by a cable 52. These cables 50, 51 and 52 hold the laterally spaced barges 46 drawn tight against the spacing frame 48 115 and prevent lateral separation of said barges which would release said frames.

It is important to note that the channel 47 is aligned with the tunnel 20 and the purpose of this channel is to permit a full 120 flow of water therethrough to the tunnel 20.

What I claim is:

1. A boat hull, a paddle wheel having a shaft mounted on the hull, a motor, and driving connections from the motor to the paddle wheel, said motor being mounted in part on said shaft to partake of angular movements therewith in respect to the hull to keep said driving connections aligned. 125

2. The structure defined in claim 1 in 130

- which said motor is further supported in part on the hull for movement in respect thereto.
3. A boat hull, a paddle wheel having a shaft mounted on the hull, two motors, and driving connections from the motors to the paddle wheel, said motors being located one at each end of the paddle wheel and mounted in part on said shaft to partake of angular movements therewith in respect to the hull to keep said driving connections aligned. 70
4. The combination with a boat hull having a recess in its stern, of a transverse shaft having its ends mounted on the hull at opposite sides of the recess, a paddle wheel in said recess journaled on the shaft, two motors mounted in part on said shaft and in part on the hull, one at each side of the recess, said motors being held to partake of the angular movements of the shaft in respect to the hull, and driving connections from each motor to the paddle wheel including a spur gear on the paddle wheel 75 and an intermeshing spur pinion on the motor. 80
5. The combination with a boat hull having a recess in its stern, of a transverse shaft spanning said recess and having its end portions mounted on the hull, a paddle wheel on the shaft within the recess, a motor having a three-point suspension, one bearing of which is on the hull structure and the other two of which are on the shaft, and driving connections from the motor to the paddle wheel. 85
6. The combination with a boat hull having a recess in its stern, of a transverse shaft spanning said recess and having its end portions mounted on the hull, a paddle wheel on the shaft within the recess, a motor having a three-point suspension, one bearing of which is on the hull structure in the form of a ball and socket joint and the other two of which are on the shaft, and driving connections from the motor to the paddle wheel. 90
7. The combination with a boat hull having a recess in its stern, of a transverse shaft spanning said recess and having its end portions mounted on the hull, a paddle wheel on the shaft within the recess, a motor having three-point suspension, one bearing of which is on the hull structure and the other two of which are on the shaft, and driving connections from the motor to the paddle wheel comprising a spur pinion on the shaft of the motor and an intermeshing spur gear on the paddle wheel. 95
8. The combination with a boat hull having a recess in its stern, of a transverse shaft spanning said recess and having its end portions mounted on the hull, a paddle wheel on the shaft within the recess, said shaft being fixed, a motor having a three-point suspension, one bearing of which is rocka- 100
- bly supported on the hull structure and the other two of which are journaled on the fixed shaft, and driving connections from the motor to the paddle wheel. 105
9. The combination with a boat hull having a recess in its stern, of a transverse shaft spanning said recess and having its end portions mounted on the hull, a paddle wheel on the shaft within the recess, a motor on the hull at each side of the recess having three-point suspension, one bearing of each motor being rockably supported on the hull structure and the other two bearings thereof being on the shaft, a spur gear on each end of the paddle wheel, and spur pinions on the shafts of the motors and meshing with said gears. 110
10. The combination with a boat hull having a recess in its stern, of a transverse shaft spanning said recess and having its end portions mounted on the hull, a paddle wheel on the shaft within the recess, a motor on the hull on each side of the recess and having three-point suspension, one bearing of each motor being rockably supported on the hull structure and the other two bearings thereof being on the shaft, a spur gear on each end of the paddle wheel, and spur pinions on the shaft of the motors and meshing with said gears, said paddle wheel comprising two axially spaced sections, each of which is independently driven by the motor to which it is connected. 115
11. A boat hull having a tunnel extending longitudinally thereof and a recess in its stern longitudinally aligned with said tunnel, in combination with a transverse shaft spanning the tunnel exposed in said recess and having its end portions mounted on the hull, a paddle wheel on the shaft within the recess, a motor having a three-point suspension, one bearing of which is on the hull structure and the other two of which are on the shaft, and driving connections from the motor to the paddle wheel. 120
12. A boat hull having a tunnel extending longitudinally thereof and a recess in its stern longitudinally aligned with the tunnel, in combination with a transverse shaft spanning the tunnel exposed in said recess and having its end portions mounted on the hull, a paddle wheel on the shaft within the recess, a motor having a three-point suspension, one bearing of which is on the hull structure in the form of a ball and socket joint and the other two of which are on the shaft, and driving connections from the motor to the paddle wheel. 125
13. A boat hull having a tunnel extending longitudinally thereof and a recess in its stern longitudinally aligned with said tunnel, in combination with a transverse shaft spanning the tunnel exposed in said recess and having its end portions mounted on the hull, a paddle wheel on the shaft within the recess, a motor having a three-point suspension, one bearing of which is on the hull structure and the other two of which are on the shaft, and driving connections from the motor to the paddle wheel. 130

the recess, a motor having a three-point suspension, one bearing of which is on the hull structure and the other two of which are on the shaft, and driving connections from the 5 motor to the paddle wheel comprising a spur pinion on the shaft of the motor and an intermeshing spur gear on the paddle wheel.

14. A boat hull having a tunnel extending longitudinally thereof and a recess in its 10 stern longitudinally aligned with said tunnel, in combination with a transverse shaft spanning the tunnel exposed in said recess and having its end portions mounted on the hull, a paddle wheel on the shaft within the 15 recess, said shaft being fixed, a motor having a three-point suspension, one bearing of which is rockably supported on the hull structure and the other two of which are journaled on the fixed shaft, and driving 20 connections from the motor to the paddle wheel.

15. A boat hull having a tunnel extending longitudinally thereof and a recess in its stern longitudinally aligned with said tunnel, 25 in combination with a transverse shaft spanning the tunnel exposed in said recess and having its end portions mounted on the hull, a paddle wheel on the shaft within the recess, a motor on the hull at each side of the recess having three-point suspension, one 30 bearing of each motor being rockably supported on the hull structure and the other two bearings thereof being on the shaft, a spur gear on each end of the paddle wheel,

and spur pinions on the shafts of the motors 35 and meshing with said gears.

16. A boat hull having a tunnel extending longitudinally thereof and a recess in its stern longitudinally aligned with said tunnel in combination with a transverse shaft spanning the tunnel exposed in said recess and having its end portions mounted on the hull, a paddle wheel on the shaft within the recess, a motor on the hull on each side of the recess and having three-point suspension, 40 one bearing of each motor being rockably supported on the hull structure and the other two bearings thereof being on the shaft, a spur gear on each end of the paddle wheel, 45 and spur pinions on the shafts of the motors 50 and meshing with said gears, said paddle wheel comprising two axially spaced sections, each of which is independently driven by the motor to which it is connected.

17. A boat hull having a tunnel extending longitudinally thereof and a recess in its stern longitudinally aligned with said tunnel, said hull having a pair of girders on each side of said tunnel, pairs of pedestals mounted directly over the pairs of girders 60 and rigidly secured in respect thereto, a transverse shaft spanning the tunnel exposed in said recess and having its end portions mounted on the pedestals and rigidly secured thereto, and a paddle wheel journaled 65 on the shaft within said recess.

In testimony whereof I affix my signature,
FRANCIS M. HENRY.
